UNITED STATES PATENT OFFICE.

CHARLES W. GLIDDEN, OF LYNN, ASSIGNOR TO JAMES W. BROOKS, TRUSTEE,
OF CAMBRIDGE, MASSACHUSETTS.

HEEL-TRIMMING MACHINE.

SPECIFICATION forming part of Letters Patent No. 411,655, dated September 24, 1889.

Application filed May 28, 1888. Renewed May 18, 1889. Serial No. 311,306. (No model.)

To all whom it may concern:

Be it known that I, CHARLES W. GLIDDEN, of Lynn, county of Essex, and State of Massachusetts, have invented an Improvement in 5 Heel-Trimming Machines, of which the following description, in connection with the accompanying drawings, is a specification, like letters on the drawings representing like parts.

This invention is an improvement on that 10 class of machines having a rotary cutter, and, as herein shown, the machine has a jack to hold the shoe having the heel to be trimmed, my invention being herein shown as applied to a machine of a class represented in United 15 States Patent No. 267,544, dated Nov. 14, 1882. The machine described in the said patent has a rock-shaft provided with a rearwardly-extended arm, on which is pivoted a three-armed jack free to rock on its pivots and to 20 rise and fall at its shoe-carrying end as the operator, rotating the shoe by hand, keeps the heel-pattern pressed against the guide-plate at the rear side of the cutter employed to trim the heel. In my experiments with this 25 class of machines I have ascertained that the jack, besides its two motions provided for in the said patent, should have a third or longitudinal or sliding movement while the heel is being trimmed at its sides or between the 30 corners of the breast and the rounded rear part of the heel, for by such sliding movement of the jack the trimming is better done and the work is kept better in view of the operator. I have provided the machine herein described with means whereby this longitudinal 35 movement of the jack (very nearly like the jack in the said patent) is made automatic.

The machine is provided with a cam, which at the proper times, as will be described, acts 40 to move the jack longitudinally, the cam being herein shown as set in motion by the shaft of the heel or heel-pattern. I have also combined with the rotary cutter a rand or counter guard, which I have supported in a 45 peculiar manner—viz., in a carriage mounted upon curved tracks, the said carriage being made movable at the proper times thereon toward and from the rotary cutter having blades adapted to trim the main body of the heel, I de- 50 nominating the said cutter as a "molded" cut-

ter because its blades are and will be shaped or molded at their edges to correspond with the shape which it is desired to give to the heel in the direction of its height. The movement of the rand or counter guard, as described, enables it to uncover more or less of the molded cutter, according to whether the molded cutter is acting upon the rear part or sides of the heel, the said movement being made automatic by the movement of the jack, 55 the cutter being connected to the carriage which supports the rand or counter guard. I have also made the said carriage to hold a shaft having at one end a rand-cutter, the said shaft having a pulley for the reception of a 60 belt by which to rotate it at the desired speed.

Figure 1 is a front elevation of a heel-trimming machine embodying my invention. Fig. 1^a is a detail showing the carriage and the tracks. Fig. 2 is a left-hand end elevation of the machine shown in Fig. 1. Fig. 3 is a top or plan view thereof. Fig. 4 is a sectional detail of a part of the machine, taken in the line x, Fig. 3. Fig. 5 is a section of Fig. 4 in the dotted line x'. Fig. 6 is a detail 75 supposed to be taken from the rear side of Fig. 4, but reversed to show the cam and some of the means for moving it to impart to the jack its longitudinal movement. Fig. 7 is a partial section of the machine in dotted 80 line x², Fig. 3, chiefly to show the molded cutter, its actuating-shaft, the rand-cutter, the rand or counter guard, and carriage supporting the latter. Fig. 8 is a partial section in the dotted line x³ of Fig. 7, looking to the 85 right, the rand or counter guard and carriage being, however, omitted, the view being made chiefly to show the shape of the rand-cutter and the location of its cutting-edges with relation to the knives or blades of the molded 90 cutter; and Fig. 9 shows several details of the heel-pattern against which the tread end of the heel is clamped.

The standard B², the arm L thereon, its stem n³, made adjustable in the arm L, the 95 screw N², to raise and lower the stem g, the frame H, and the rock-shaft K, mounted upon point-screws and carrying a jack, to be described, are and may be all substantially as in United States Patent No. 267,544, with the 100

exception that the frame H is herein stationary and extended upwardly, as will be described.

The standard B² receives in it the rotating cutter-carrying shaft A, to the forward end of which is attached, in usual manner, a molded cutter A', having blades, as a, the cutting-edges of which are shaped to correspond with the shape of the heel in the direction of its height. The shaft A is extended through a long sleeve-like bearing A², (see Fig. 7,) upon which is secured by a screw A³ a collar A⁴, the said sleeve-bearing being surrounded between the said collar A⁴ and a shoulder at the end of the hub of the molded cutter by a sleeve A⁵, to which in turn, by a screw A⁶, is secured a guard A⁷, against the periphery of which at the rear side of the molded cutter bears the heel-pattern A⁸. The heel-pattern A⁸ is connected to the end of a short shaft A⁹, having its bearings in a hub A¹⁰ at the front end of the arm A¹² of a jack, the other arm being shown at A¹³, the said arms being shaped (see Fig. 3) to form a nearly U-shaped yoke. The inner end of the shaft A⁹ abuts against a stop-screw 240 in the hub A¹⁰ and prevents undue longitudinal movement of the shaft. The shaft A⁹, carried by the arm A¹² of the jack, has fast upon it at the rear side of the heel-pattern a gear a', (see Figs. 1, 2, and 9,) which engages an intermediate gear a², (see Figs. 2 and 3,) supported on a suitable stud a³ on the arm A¹², the said intermediate gear engaging the teeth of a toothed gear a³ and rotating the same as the operator, grasping the shoe in his hand, turns the heel thereon under the molded cutter. The gear a³ has fast to it a toothed gear a⁴, both loose on a suitable stud a⁵, carried by the jack, the gear a⁴, of larger diameter, engaging the teeth of a rack-bar a⁶, connected to and forming part of a slide a⁷, slotted, as shown by dotted lines in Fig. 2, and adapted to slide backward or forward on the guide-stud a⁸ of the arm A¹² of the jack, the said slide having extended back from it a rod a⁹, (shown in Figs. 3, 4, and 6,) to which is attached a rack-plate a¹⁰, the teeth of the said rack-plate engaging a toothed gear a¹², loose on a stud a¹³, extended laterally from one side of the depending part b²⁰ of a rocker b⁸, to be described. The toothed gear a¹² has a sleeve which carries a cam a¹⁴, into the slot of which is entered a roller or other pin a¹⁵, extended from a depending flange 8 (see Figs. 4 and 5) of the rigid extension or saddle portion B of the jack A¹² A¹³, which carries the shoe the heel of which is to be trimmed.

The heel-pattern A⁸ is slotted, as at 2, (see Fig. 9,) to receive a slide-block 3, to which is attached the rest 4, against which is placed the breast of the heel, the screw 5, attaching the said rest to the block, in practice being extended through and clamping the said block 6 to the heel-pattern plate, the block having a pin 6 to enter the tread of the heel. The arm A¹³ of the jack has at its end a short shaft b,

provided with a pinion b', (shown by dotted lines, Fig. 3,) which engages teeth of a slide-rod b², of usual construction, and provided at its inner end with a suitable head to bear against the neck of a last, if in the shoe, or against the inner sole of the shoe to thus clamp the heel in position in usual manner against the heel or pattern plate. 75

The rocking lever K, supported upon point-screws b⁴ in the stationary frame H, has extended from it at or near the center of its length an arm or extension K', preferably made tubular for lightness, to which extension, by set-screws b⁵, are attached blocks b⁶, (see Fig. 4,) the latter receiving and having fixed in them by the said screws b⁵ a pivot-pin b⁷, the pointed ends of which serve as the journals for a rocker b⁸, the said rocker at its outer end having a bearing-screw b⁹, which is provided with a conical recess to fit one end of the pivot-pin b⁷. 80

The rocker b⁸ (see Fig. 5) has at its opposite sides wings or tracks b²⁰, which are embraced by the guideways of the saddle-like extension B of the jack, the said saddle-like extension being free to slide longitudinally upon the said tracks b⁹, thus permitting the jack to be moved longitudinally, as when the side of the heel is being trimmed, the rocker b⁸, having the ways on which slides the saddle portion of the jack, itself rocking upon the pivot-pin b⁷ and permitting the jack to tip, as required, as when the molded cutter is trimming about the rear part of the heel. 90

In practice the lug b¹⁰ at the end of the rocker b⁸ will have attached to it a treadle-rod, as in the patent referred to. The stem g, at its lower end at each side, has a plate c', having a track 10, (see Fig. 1,) upon which track rest and travel rolls 12 on studs 13 at each side of a carriage c², (shown separately in Fig. 1^a,) the said carriage having suitable bearings for the reception of a shaft d, having fast upon it between the said bearings a belt-pulley d', and at the inner end of the shaft is a head d^x, to which, by suitable screws 15, is attached a rand-cutter d², it having, as shown, three blades having upturned lips, as best shown in Fig. 7, to overlap, as it were, the cutting-edges of the knives or blades a to thus avoid a fin. The carriage c² has an extension c^x, provided with a hole or socket 16, in which is placed the round head (see dotted lines, Fig. 3,) of a connecting-pin 17, the shank of which enters loosely a hole 17^x in the end of an arm e, which arm at its rear end is threaded to receive a screw, as e', free to rotate in a yoke e² at one end of an arm e³, pivoted at e⁴ upon an arm e⁵, the said arm having a tubular shank e⁶, forked or bifurcated at its lower end to constitute two slotted feet e⁷, the said slotted feet having surfaces 18, (see Figs. 3 and 4,) which rest on rolls 19 of studs 20, extended from ears 21, erected upon the saddle-like extension B of the jack, the said rolls rolling in the slots of the said feet when the jack and its saddle-like exten- 100 105 110 115 120 125 130

sion B is moved longitudinally, the ears 21 within and between the opposite feet causing the arms e^6 to follow the jack and saddle in their rocking movement, and consequently 5 as the jack and saddle are rocked the pin 17, carried by the arm e , (the said pin entering the hole i^6 of the extension c^8 of the carriage c^2), causes the said carriage to move toward and from the molded cutter in such direction 10 as to cause the lip 25 of the rand or counter guard b —it entering the rand-crease—to follow the contour of the edges of the knives or blades a of the molded cutter as more or less of the cutters or blades are being uncovered, the direction of movement of the rand or counter guard being controlled further by the shape of the track upon which the rolls 15 12 of the carriage c^2 ride.

In this my invention the curve of the track 20 10, upon which the rolls 12 run, is described from a center common to the curve given to the outer or heel-seat end of knives or blades a , the said center being designated in Fig. 1 by 26. The frame H is extended above the 25 jack and provided with a cross-bar H' , which is prolonged by a hollow post H^2 , which is connected with the upright H at the opposite side of the machine, as best seen in Fig. 3. The shaft A has fast upon it a pulley D, which 30 receives any usual driving-belt by which to rotate the shaft, the said shaft having a second belt-pulley D' , from which will extend a belt (not shown) over a belt-pulley D^2 , fast on a shaft D^3 , extended through the hollow portion 35 H^2 of the cross-bar H' , the said portion being made tubular for such purpose, the opposite end of the shaft B^3 having fast upon it a belt-pulley D^4 , which in practice will receive and drive a belt, (not shown,) which 40 will be extended over the pulley d' , before described as fast on the shaft d of the rand-cutter. The screw e' is restrained from longitudinal motion in the head e^2 of the arm e^3 ; but by the rotation of the said screw the arm 45 e , and with it the carriage c^2 , may be adjusted with relation to the arm e^3 according to the thickness of the heel being trimmed.

In another application, Serial No. 275,880, filed on the 2d day of June, 1888, I have 50 shown a carriage, substantially such as herein shown; but the same is represented as mounted upon links, and so the said carriage, with its rand or counter guard and rand-cutter, is not herein broadly claimed.

55 I do not desire to limit my invention to the exact construction of the jack herein shown or to the exact construction of the means employed for giving to the jack, in addition to its rising and falling and rocking movement, a sliding movement, as described.

The operator, having jacked the shoe through the action of the spindle b^2 , which confines the tread-lift of the heel closely against the pattern-plate, and while the forward end of the jack is depressed through the 60 usual treadle common to the patent referred to, removes his foot from the treadle and per-

mits the pattern-plate of the jack to rise in contact with the pattern-guide, with the corner of the breast of the heel in position to be 70 acted upon by the rotary trimming-cutter. In this condition of the parts, the toe of a shoe being a little above the horizontal and with the toe of the shoe pointed toward the operator, and the operator grasping the same, he 75 commences to turn the shoe, depressing the toe, such movement of the shoe acting quickly through the gears and devices described carried by the jack to turn the cam a^4 and push the jack forward rapidly toward the 80 operator, this forward motion taking place while the cutter, which is always in rotation, acts to trim the heel from one corner of the breast to the commencement of what is to be the substantially circular rear part of 85 the heel. As soon as that portion of the heel which is to be trimmed substantially circular arrives under the cutter the longitudinal motion of the jack is suspended, by reason of the shape of the cam, until the operator has turned 90 the shoe sufficiently to effect the trimming of the substantially circular rear part thereof, the toe of the shoe at such time being below a longitudinal line and pointed away from the operator. The substantially circular part 95 of the heel having been trimmed, the operator, by the further movement of the shoe through the gearing connected with the pattern-plate and between it and the said cam a^4 , causes the said cam to continue to slide the jack toward the operator, while the rotary cutter 100 acts to trim the opposite side of the heel, or from the substantially circular part thereof to the breast corner opposite that where the trimming was commenced. It will be noticed 105 that the position of the top-lift end of the heel with relation to the center of the rotary cutter is determined by the pattern-plate, which bears against the pattern-guide, as in the patent referred to, and it will be remembered that the edge or lip of the rand or counter guard enters the rand-crease, and the shoe, by reason of the usual weights or attachments upon the jack, is pressed up firmly 110 against the said rand or counter guard, so 115 that it acts to position the heel-seat end of the heel with relation to the center of the cutter. It will be noticed that when the substantially circular rear part of the heel is being trimmed the said heel, owing to its 120 pitch, and being pressed upwardly against the two fixed points—namely, the pattern-guide and the rand or counter guard—must have a tendency to tip, the extent of tipping depending upon the pitch of the heel, or the difference in size between the top-lift and the heel-seat end of the heel. To accommodate for this tipping of the jack the latter has been mounted upon the rocker b^8 . As the shoe is tipped, as 125 described, the carrier c^2 , to which the rand or counter guard is attached, is moved automatically and positively by or through the connection previously described between the said carrier and the jack, thus moving the

rand or counter guard to uncover more of the cutting-edges of the blades, the carrier at such time being moved upon the track 10, and as the carrier is so moved it is tipped positively 5 to thus enable it to remain with its edge parallel to and to properly enter the rand-crease.

In the machine herein described it will be noticed that the rand-crease is not depended upon, as has heretofore been the case, to move 10 the rand or counter guard to uncover more or less of the cutting-edges of the plates; but, on the contrary, the said rand-guard is moved positively, which results in the more symmetrical trimming of the heel, especially such 15 heels as contain soft stock, which is very apt to be the case in shoes of low cost.

I claim—

1. In a heel-trimming machine, the combination, with a rotary cutter and a jack to 20 hold the shoe the heel of which is to be trimmed, of a pattern-plate and operative mechanism to automatically impart to the said jack a longitudinally-sliding motion while the said cutter acts to trim the sides of 25 the heel, substantially as and for the purposes described.

2. In a heel-trimming machine, a rocking lever and a rocker-frame pivoted thereon, having a track, combined with a jack and 30 with a cam to slide the jack longitudinally upon the said track, substantially as described.

3. In a heel-trimming machine, a rocking lever and a rocker-frame pivoted transversely 35 thereon, having a track, combined with a jack having an extension B fitted to and adapted to slide longitudinally upon the said track, and with a cam intermediate the said rocker-frame and jack to automatically move 40 the jack longitudinally upon the rocker-frame, substantially as described.

4. The combination, in a heel-trimming machine, of the following instrumentalities, 45 namely: a rotary cutter, a sliding jack to hold the shoe the heel of which is to be trimmed, a rocking support for the said jack, a pattern-plate, and a cam moved by it to change the relative positions of the jack and cutter, substantially as described, whereby the heel is 50 presented to the action of the cutter by a substantially right line movement when the side of the heel is being trimmed, substantially as described.

5. The rocking lever, the rocker mounted 55 thereon and provided with a track, the jack mounted to slide upon the rocker, and a cam to move the jack longitudinally with relation to the cutter while the sides of the heel are

being trimmed, combined with the pattern-plate, the gears, guard a^o , and rack bars or 60 plates to actuate the said cam as the pattern-plate is rotated, substantially as described.

6. In a heel-trimming machine, a rotating molded cutter and a carriage having an attached rand or counter guard, combined with 65 a track, as 10, upon which the counter-guard-supporting carriage travels when uncovering more or less of the knives or blades of the molded cutter, substantially as described.

7. In a heel-trimming machine, a rotating 70 cutter and a carriage having an attached rand or counter guard, combined with a track upon which the said counter-guard-supporting carriage travels when uncovering more or less of the knives or blades of the cutter, 75 and with a tipping jack and connections between the said jack and carriage to automatically move the carriage, substantially as described.

8. In a heel-trimming machine, a rotating 80 cutter and a carriage having an attached rand or counter guard, combined with a track, as 10, upon which the said carriage is supported and travels when uncovering more or less of the knives or blades of the cutter, and 85 with an independently-rotating rand-cutter carried by the said carriage, substantially as described.

9. In a heel-trimming machine, a rotating cutter, a carriage, a rand or counter guard, 90 and a rand-cutter mounted in the said carriage, a track upon which the said carriage moves, and a tipping jack, combined with connections, substantially as described, between the said jack and carriage, to operate 95 substantially as described.

10. The rotary cutter and the jack to hold the shoe the heel of which is to be trimmed, combined with a track, as 10, an independent carriage upon said track, a rand or counter 100 guard attached to the said carriage, the shaft d , having its bearings in the said carriage, the rand-cutter attached to the said shaft d , and connections between the jack and carriage, whereby the jack as it is tipped also 105 moves the carriage on the said track and with it the said rand-cutter and rand-guard, substantially as described.

In testimony whereof I have signed my name to this specification in the presence of 110 two subscribing witnesses.

CHARLES W. GLIDDEN.
